US0D1040664S

(12) **United States Design Patent** (10) **Patent No.:** **US D1,040,664 S**
(45) **Date of Patent:** **** Sep. 3, 2024**

(54) **POUCH**

(71) Applicant: **Henkel AG & Co. KGaA**, Duesseldorf (DE)

(72) Inventor: **Emil Tarnowsky**, Brampton (CA)

(73) Assignee: **Henkel AG & Co. KGaA**, Duesseldorf (DE)

(**) Term: **15 Years**

(21) Appl. No.: **29/837,655**

(22) Filed: **May 6, 2022**

(51) LOC (14) Cl. **09-05**

(52) U.S. Cl.

USPC **D9/707**; D28/8.1

(58) **Field of Classification Search**

USPC D23/202, 225; D9/707; D28/8.1

CPC B65B 2230/02; B65D 1/36; B65D 65/46;

C11D 17/045

See application file for complete search history.

(57)

CLAIM

The ornamental design for a pouch, as shown and described.

DESCRIPTION

FIG. 1 is a top, front isometric view of a pouch showing the claimed design;

FIG. 2 is a bottom, rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures show portions of the pouch that form no part of the claimed design.

1 Claim, 4 Drawing Sheets
